US00D815157S

(12) **United States Design Patent** (10) Patent No.: **US D815,157 S**
Cloutier Boily (45) Date of Patent: **** Apr. 10, 2018**

(54) METER ROLLER FOR AN AGRICULTURAL METERING SYSTEM	4,264,023 A	4/1981	Stocks et al.
	4,379,664 A	4/1983	Klein et al.
	4,408,704 A *	10/1983	Steilen A01C 7/123 111/177
(71) Applicant: CNH Industrial Canada, Ltd. , Saskatoon (CA)	4,453,866 A	6/1984	Ryan
	4,500,017 A	2/1985	Machnee
(72) Inventor: Guillaume Cloutier Boily , Martensville (CA)	4,537,333 A	8/1985	Bjerregaard
	4,600,122 A	7/1986	Lundie et al.
	4,896,616 A	1/1990	Wintersteiger et al.
(73) Assignee: CNH Industrial Canada, Ltd. , Saskatoon, Saskatchewan (CA)	(Continued)		
(**) Term: 15 Years	FOREIGN PATENT DOCUMENTS		
(21) Appl. No.: 29/596,846	AU	2007201262	4/2007
(22) Filed: Mar. 10, 2017	WO	2016135174	9/2016
(51) LOC (11) Cl. 15-03	WO	WO2016135174	9/2016
(52) U.S. Cl. USPC D15/28			
(58) Field of Classification Search USPC ..... D15/10, 13, 21, 28; 222/312, 314, 317; 406/68 CPC A01C 15/16; A01C 15/14; A01C 15/005; A01C 7/00; A01C 7/06; A01C 7/12; A01C 7/08; A01C 7/04; A01C 7/16; A01C 7/123; A01C 7/087; A01C 7/20; B02C 13/09; B02C 13/095; B02C 13/20; B65G 65/4881; B65G 65/00; B65G 65/48; B65G 53/4633; Y10S 111/90; Y10S 111/922

U.S. PATENT DOCUMENTS

3,447,758 A	6/1969	Oznobichine
3,606,965 A	9/1971	Cortelyou
3,954,204 A	5/1976	Becker
3,982,670 A	9/1976	Brass
4,023,511 A	5/1977	Newman
4,053,088 A	10/1977	Grataloup
4,254,897 A	3/1981	Stocks

FIG. 1 is a perspective view of a meter roller for an agricultural metering system;
FIG. 2 is a top view of the meter roller; and,
FIG. 3 is a cross-sectional view of the meter roller, taken along line 3-3 of FIG. 2.
Phantom lines, where utilized, are for illustrative purposes only and form no part of the claimed design.
